UNITED STATES PATENT OFFICE.

VICTOR R. WILL, OF LODI, CALIFORNIA, ASSIGNOR TO P-A-T-S MANUFACTURING COMPANY, OF LODI, CALIFORNIA, A CORPORATION.

DESIGN FOR AN AUTOMOBILE DIRECTION-SIGNAL.

56,047.

Specification for Design.

Patented Aug. 10, 1920.

Application filed February 16, 1920. Serial No. 359,187. Term of patent 14 years.

To all whom it may concern:

Be it known that I, VICTOR R. WILL, a citizen of the United States, residing at Lodi, in the county of San Joaquin and State of California, have invented a new, original, and ornamental Design for an Automobile Direction-Signal, of which the following is a specification, reference being had to the accompanying drawing, forming

part thereof, which shows a side elevation of the device.

I claim:—

The ornamental design for an automobile direction signal as shown.

VICTOR R. WILL.
